By James L. Morris.

UNITED STATES PATENT OFFICE.

WILLIAM GEE, OF NEW YORK, N. Y.

ELECTRIC BURGLAR AND FIRE ALARM.

SPECIFICATION forming part of Letters Patent No. 423,753, dated March 18, 1890.

Application filed November 19, 1889. Serial No. 330,829. (No model.)

To all whom it may concern:

Be it known that I, WILLIAM GEE, a citizen of the United States, residing at New York, in the county of New York and State of New York, have invented new and useful Improvements in Electric Burglar and Fire Alarms, of which the following is a specification.

My invention relates to devices for making and breaking the circuit of an electric burglar or other similar alarm in which the circuit is established and the alarm operated by the opening or moving of a door or window-sash for obtaining ingress to a building or room surreptitiously.

It is the purpose of my said invention to provide a novel and simple circuit-closing attachment capable of being applied to and removed from a door or window instantaneously and without marring the wood-work, means being provided whereby the attachment may be fitted to an entrance opening of any construction with due compensation for the want of a proper engagement between the movable and the immovable parts, or, in other words, for the varying degree of accuracy with which doors and windows in different parts of the same house, as well as in separate houses, fit within their jambs. It is one purpose, therefore, of my invention to provide simple means, easily operated without previous skill or special experience, whereby such attachment shall be rendered applicable without change other than adjustment of the parts of the attachment, in order to adapt them to different locations and to different constructions of the parts with which said attachment is connected.

It is a further purpose of my invention to combine with an electric burglar-alarm a thermo-electric indicator capable of being set or adjusted in such manner that it shall respond operatively to a rise of temperature passing any given point upon the thermic scale, according to the adjustment given to the heat-indicating and circuit-closing mechanism.

The invention consists in the several novel features of construction and new combinations of parts hereinafter fully set forth, and then definitely pointed out in the claims following this specification.

In order to enable others skilled in the art to practice my said invention, I will proceed to describe the same in detail, reference being made to the accompanying drawings, in which—

Figure 1 is a front elevation and diagram of an apparatus embodying my invention. Fig. 1^a is an end elevation of the casing, showing the removable cover and bottom. Fig. 2 is an end elevation of the thermostat, the battery, bell, and burglar-alarm being removed. Fig. 3 is a detail view of the scale-plate, showing its attachments. Fig. 4 is a detail side elevation of the circuit-making and circuit-breaking attachment removed from connection with the door or window. Fig. 5 is a plan view of the same, showing the wire-connecting clip. Fig. 6 is a detail view showing the construction of the joint connecting the parts of the device shown in Figs. 4 and 5. Fig. 7 is a detail view of the wire-connecting clip. Fig. 8 is a sectional view of the parts shown in Fig. 6.

In the said drawings, the reference-numeral 1 denotes the casing or frame within which the operative parts are assembled. Attached to the vertical wall thereof is a bracket 2, having a circular plate 3 standing at right angles to the supporting-wall, and having a central opening to receive the end of the stem 4. Upon this stem I mount a series of expansion-disks 5, each consisting of a chamber of cylindrical form constructed of two sheets of thin metal joined at their edges to form a tight hermetically-sealed receptacle. One of the sheet-metal portions of each expansion-disk may be provided with circular concentric corrugations to increase the surface area, and in this as well as other respects the construction of these expansion-disks does not materially differ from that set forth in the Letters Patent granted to me the 18th day of January, 1887, No. 356,360. The said disks are arranged within a frame composed of three parallel rods 6, which pass through openings in the circular plate 3 near its edge, their other ends being similarly secured in a separate circular plate 7, slightly less in diameter than the plate 3. Upon that one of the disks 5 which is most remote from the plate 3 is formed or mounted a neck, stem, or spindle 8,

which passes through a central opening in the circular plate 7. This plate is provided with a flat extension-piece 9, projecting from that edge next to the wall of the casing and having no further connection with said wall.

Formed or mounted upon the outer edge of the plate 7 is a flat metallic bracket 10, which extends parallel with the axis of the frame containing the expansion-disks to the center of 10 said frame, or thereabout, from which point it is carried directly upward at right angles with the horizontal portion. Upon the upper end of the vertical member of the frame is mounted an arc-shaped plate 12, graduated to 15 form a thermal scale.

Upon the extension-piece 9 is mounted a bracket-support 13, having a foot which is provided with an elongated slot 14, through which the attaching-screw passes, thus enabling the 20 bracket to be supported and adjusted upon the horizontal extension-piece 9. Upon the outer end of the bracket-support 13 is formed a nipple 15, which receives a pivotal bearing 16, upon which is mounted a lever 17, one 25 end whereof is connected to the end of the stem or neck 8. The other end of said lever is provided with an enlargement 18, which receives a pivot-pin 19, having an under-beveled head, between which and the oppositely- 30 beveled end of the enlargement 18 the end of a link 20 engages. This link is substantially parallel with the horizontal member of the bracket 10. Upon the vertical member of this bracket is attached a pivot-pin 21, upon 35 which is mounted an index-arm 22, having its end which drops below the pivot-pin 21 connected to the link 20. It will be seen that by this construction and arrangement of parts the expansion and contraction of the disks 5 40 will advance and retract the stem or neck 8 and advance and retract the point of the index-arm upon the graduated scale.

Upon the vertical member of the bracket-frame 10 is mounted a binding-post 23, which 45 is not in electrical engagement with the scale-plate 12 by reason of the fact that the latter is insulated from the vertical arm of the bracket by means of rubber or wooden disks 24, care being taken to prevent the contact of 50 the fastening-screws 25. A binding-post 26 is mounted upon the scale-plate 12, which is also provided with a movable slide 27, having a set-screw 28, by which it may be clamped at any point to which it is adjusted. Upon 55 one face of this slide is a platinum contact-point 29, and a platinum tip 30, mounted upon the point of the index-arm, sweeps over the scale, and under proper conditions makes contact with the contact on the slide.

60 To attract attention to the fact that the temperature has risen to a "danger" point, I employ a simple electric bell 31, or other form of alarm, which is operated, preferably, by a dry battery 32, though any other form of open-circuit battery may be employed. I have 65 shown the alarm arranged in the same casing

with the other mechanism; but this is merely for the sake of illustration, as it may be, and usually is, located at some distant point, such as an office, engine-house, or other suitable 70 point.

The electrical connections are as follows: A wire 33 leads from one pole of the battery to the binding-post 23, and the binding-post 26 is connected by a wire 34 with one of the 75 binding-posts 35 of the electric bell. A wire 36 leads from the other binding-post of the bell mechanism back to the other pole of the battery, and the circuit is established by the contact of the platinum point 29 and tip 30. 80 By adjusting the slide 27 the alarm may be caused to sound at any temperature indicated by the scale-plate, and it is evident, also, that by a simple reversal of arrangement a low temperature may be announced as well as the 85 opposite.

The casing 1 is provided with a removable cover or lid 37, having a bottom 38, and when the apparatus is in use both are thrown open to permit a free access of heat to the apparatus. 90

With the apparatus thus described I combine a burglar-alarm so constructed that it is detachable from and attachable to any of the ordinary points of entrance to a building. 95 This part of my invention consists of what I term an "electric wedge," composed of two plates 39 and 40, formed of brass. At its end the plate 40 is provided with a transverse slot 41, having such dimensions that it will admit 100 the end of the plate 39, which is provided with two short longitudinal slots 42. After insertion the two outside prongs 43 are turned toward the end of the plate 40, and the central portion 44 is turned in the opposite direction, 105 riveting the two parts firmly together and holding them normally in the position shown, in which the parts converge at a small angle to a point when viewed in side elevation, forming a wedge. The upper member of this 110 wedge is preferably provided with a corrugated surface 45, beyond which the plate 39 is bent into vertical position to form a shoulder 46. It is then bent into or nearly into 115 parallelism with the lower plate 40.

The plate 40 is provided with a wooden wedge 47, adjustable longitudinally thereon. Between the two plates 39 and 40 is interposed a U-shaped spring 48, one arm of 120 which is riveted to the upper plate 39, while the other arm lies in a central groove or channel 49 in the wedge 47. This wedge is provided with a channel in its lower face, which receives the plate 40 and serves to 125 guide the longitudinal adjustment of the wedge.

Upon the free end of the plate 40, but entirely insulated from it by rubber or other disks 50, is a screw 51, which projects upward through an opening 52 in the free end of the 130 plate 39, such opening being of considerably greater diameter than the screw to prevent

accidental contact. Upon the screw 51, above the end of plate 39, is turned a nut 53, which is adjustable upon the screw. When the wedge is used, it is inserted between the edge 5 54 and the jamb 55 of a closed door or window, whereby the diverging members or portions of the two plates 39 and 40 are forced more or less closely together, according to the accuracy with which the door or window is 10 fitted in the jamb. The free end of the plate 39 is depressed thereby and removed from contact with the thumb-nut 53. If the space between the door and jamb or between the window and jamb is greater than usual, the 15 wedge 47 is adjusted to place the spring 48 under sufficient tension, so that when the door or window is opened it will lift the plate 39 into contact with the thumb-nut 53. The nut is then adjusted to any desired point, provided, only, that it shall remain out of contact with the plate 39 as long as the door or window remains undisturbed. When thus arranged, a clip 56, of brass or other suitable metal, is attached to the plate 39 and connected by a wire 57 to a binding-post 58, and thence by a wire 59 to the wire 34. The screw 51 is connected by a wire 60 to a binding-post 61, and thence by a wire 62 to the wire 33. The instant the door is disturbed or 25 the window raised the wedge portion of the device is released, and the circuit is established through wire 33, wire 62, binding-post 61, wire 60, screw 51, thumb-nut 53, plate 39, clip 56, wire 57, binding-post 58 and wire 35 59, wire 34, alarm 31, and wire 36, back to battery.

The electric wedge may be easily and quickly applied to any door, window, or any other part of a building, and adjusted in a 40 magnet to any desired point. It does not mark or mar the wood-work, is absolutely certain in action, is comparatively inexpensive, and is so simple as to be readily and easily understood and operated by any person. 45

What I claim is—

1. The combination, with a series or train of connected expansible disks having a stem or neck at one end of the train, of a lever 50 pivotally connected at one end to said stem and at the other end to a link, pivoted index-arm having its end connected to said link, an arc-shaped scale-plate insulated from its support, a slide adjustable on said scale-plate 55 and having a contact-point adapted to engage a tip upon the index, an alarm mechanism, and a battery connected with the conducting-support for the index and with the scale-plate through the alarm mechanism, substantially as described.

2. The combination, with a series or train of connected expansion-disks having a stem or neck moved by such expansion, of a lever mounted upon an adjustable support and connected at one end to said stem, a link con-

nected to the other end of said lever, an index-arm pivoted upon a conducting support or bracket and connected to the link, a scale-plate over which the index sweeps, a slide adjustable upon and having a set-screw clamping it to said scale-plate, said slide having a platinum tip on the index, an alarm mechanism connected to one pole of a battery and to the scale-plate, and a battery connected to the conducting-support for the index and to the bell mechanism, substantially as described. 70 75

3. In an automatic alarm, a circuit-making device composed of two diverging conducting-plates adapted to be compressed between the rigid and movable members of an entrance, one of said plates being provided with a screw-bolt insulated and extending upward through an opening in the other plate, a thumb-nut adjustable upon said bolt above said plate, a spring separating the plates, and wires connecting a battery with an audible alarm through the bolt, the thumb-nut, and one of the plates, substantially as described. 80 85

4. In an automatic alarm, the combination, with the conducting-plates diverging from a point of union, of a spring throwing the free ends of said plates apart, means for adjusting the tension of said spring, a screw-bolt mounted on and insulated from the free end 90 of one of said plates and having its threaded end passing through an opening in, but out of contact with, the end of the other plate, a thumb-nut adjustable on said bolt, and an audible alarm connected with one pole of a battery and with the movable plate, the other pole of the battery being connected to the insulated screw-bolt, substantially as described. 95 100

5. In an automatic alarm, the combination, with two conducting-plates diverging from their point of union at one end, of a spring separating the free ends of said plates, a longitudinally-adjustable wedge adjusting the tension of the spring, a screw-bolt mounted 105 in and insulated from the free end of the lower plate and having its threaded end projecting through an opening in the corresponding end of the upper plate, a thumb-nut adjustable on the bolt, an attachable and detachable 110 spring-clip connected to the upper plate and having a wire passing to an audible alarm, and a battery connected with said alarm and with the insulated screw-bolt, substantially 115 as described. 120

6. In an automatic alarm, the combination, with the plates of conducting material united at one end and diverging in wedge shape, and one plate being provided with a square shoulder adjacent to the diverging portions, of a 125 U-shaped spring having one member riveted to one of said plates and the other resting in a channel in an adjustable non-conducting wedge, whereby the tension of the spring is varied, a screw-bolt mounted on and insulated 130

from the end of one of said plates and having its threaded end passing through an opening in the end of the other plate, a thumb-nut adjustable on said bolt, a spring-clip connected with the movable plate, and an audible alarm and battery connected up with said parts, substantially as described.

In testimony whereof I have affixed my signature in presence of two witnesses.

WILLIAM GEE.
